TRAY FOR DARTS OR THE LIKE

Robert F. Hauck, McKean, Pa., assignor to Louis Marx & Co., Inc., New York, N.Y., a corporation of New York

Filed Feb. 27, 1967, Ser. No. 5,948

Term of patent 14 years

(Cl. D9—185)

FIG. 1

FIG. 3

FIG. 1 is a front perspective view of a tray for darts or the like embodying my new design;

FIG. 2 is a top plan view thereof; and

FIG. 3 is an end view thereof.

The dominant feature of my design resides in a tray for darts having a longitudinal partition with spaced cutouts adjacent to a side wall to define a narrow slot at one side of the partition with pairs of longitudinally and traversely aligned cut-outs through the bottom wall at the opposite side of the partition.

The broken line showing of the dart in FIGS. 1 and 2 is for illustrative purposes only.

I claim:

The ornamental design for a tray for darts or the like, as shown and described.
